UNITED STATES PATENT OFFICE.

JOSEPH BÉHA, OF THANN, GERMANY.

WATER-PURIFYING APPARATUS FOR STEAM-BOILERS.

SPECIFICATION forming part of Letters Patent No. 703,888, dated July 1, 1902.

Application filed October 15, 1901. Serial No. 78,724. (No model.)

To all whom it may concern:

Be it known that I, JOSEPH BÉHA, manufacturer, of Thann, Alsace, in the German Empire, have invented new and useful Improvements in Water-Purifying Apparatus for Steam-Boilers, of which the following is a specification, reference being had to the accompanying drawings for purposes of illustration.

- 10 This apparatus, which is arranged upon the boiler for the mechanical purification of the boiler-water, acts on the continuous-circulation principle, depending on the difference of temperature and density between the water raised from the boiler to the purifier and the column of water returning therefrom to the boiler, the velocity of the current of liquid, together with the suction, being greater the greater these differences.
- 15 In apparatus heretofore employed the difference of temperature between the ascending and descending columns of water is not very great, and hence the working is intermittent, since the direction of circulation alters according as the cooling is greater on one side or on the other. An uninterrupted circulation of water flowing in the same direction is, however, an essential condition in a satisfactory form of water-purifier. For 20 this purpose, according to the present invention, the column of water ascending the apparatus is considerably heated by the continual admission of steam from the boiler and is protected against cooling in the tubes outside the boiler by covering the latter with non-conducting material, while the cleansed water returning to the boiler passes through uncovered tubing and is cooled by a supply of feed-water in or around the tubing. The 25 cooling is likewise continuous, this new purifying apparatus being especially designed for boilers provided with a continuous feed, which practice proves to be the best for the rational generation of steam.
- 30 The water-purifier is so constructed that it first separates or decants the entering water and frees it from the lighter impurities before it filters it—that is to say, removes the heavier impurities from it.
- 35 In the accompanying drawings, Figure 1 is a vertical section through the purifier; Fig. 2, an elevation of the same; Fig. 3, a hori-

zontal section on the line A B of Fig. 1; Fig. 4, a horizontal section on the line CD of Fig. 1. Fig. 5 is a vertical cross-section of a Cornish boiler with two furnaces, showing the new purifying apparatus applied thereto. Fig. 6 is a longitudinal section of the same with the feed-water pipe opening into the return-tube. Fig. 7 is a portion of a longitudinal section showing the feed-water pipe 40 arranged around the return-tube. Fig. 8 represents a modification of the arrangement shown in Fig. 7, the return-tube being surrounded by a spiral feed-water pipe. 65

The purifier 1 is arranged upon the boiler 2 and is connected therewith by means of the siphon or inlet pipes 3, 4, and 5, said pipes, where outside the boiler, being suitably lagged or covered with a non-conductor of heat. The 70 middle inlet-pipe 4 serves to take up the heavier deposit from the bottom of the boiler, (which deposit usually consists of sulfate of calcium,) and therefore communicates with the deposit-collecting tube 6, which is provided with openings 7 and is arranged at the lowest part of the boiler. The other two inlet-pipes 3 and 5 terminate a little below the water-level and carry two scum-collecting funnels 8, having their mouths arranged in 75 opposite directions. These serve to take up the lighter impurities which rise to the surface of the water and generally consist of carbonate of calcium. The accumulation of the latter usually takes place above the flues, as 80 the ebullition of the water is more energetic at this point. The scum-collecting funnels should therefore be placed, as represented in the drawings, in a plane perpendicular to the axis of the flues. The pipe 4, which reaches 85 to the bottom of the boiler, is also provided with funnels 10 at the level of the water for the purpose of allowing a small quantity of water mixed with steam to enter the said tube, so that it shall heat the water which is ascending into the purifier in the same manner as is the case with the pipes 3 and 5. In consequence of the combined action of the steam and the insulation of that part of the pipes which is outside the boiler the water enters 90 the purifier at approximately the same temperature as is in the boiler itself.

In the arrangement shown in Fig. 6 the purified water passes back to the boiler through

the bend 11 and the unlagged return-pipe 12. An injector 13 is arranged in the return-pipe 12 near the boiler, and through this the feed-water continuously flows, and thus lowers the 5 temperature of the return column of water, at the same time forcing the circulation, and therefore augmenting the suction of the apparatus. The return-pipe 12 has its mouth open near the bottom of the boiler.

10 In the modification shown in Fig. 7 the feed-water-supply pipe 9 is connected to the return-pipe 12 near its entrance to the boiler and surrounds the pipe 12. The feed-water thus cools the descending column of water 15 without mixing with it. The feed-water pipe may also be spirally arranged around the return-pipe (see Fig. 8) in order to more efficiently cool the purified water and thence increase the circulation of the water through 20 boiler and purifier.

In consequence of the continual heating of the ascending and cooling of the descending pipe a reversal of the direction of flow of the current is prevented. As is well known, 25 sulfate of calcium separates from water at 150° centigrade, and in the present arrangement care is taken that the purifier maintains approximately this temperature uniformly, so that the matter separated is retained in the 30 filter, a result which could formerly only be obtained by the employment of chemical reagents.

The purifier shown in Figs. 1 to 4 has a two-fold object. In the first place it separates 35 the lighter scum from the inflowing water and then separates the heavier deposit and retains the latter, which would otherwise form an incrustation in the filter. The purifier consists, broadly, of a conical filtering-chamber 40 14, smaller toward the top and inclosed at top and bottom by wire-gauze diaphragms 15 and 16. At the lower end of the filtering-chamber is affixed the separating-chamber 17. The water enters through the bends 18 into an 45 annular chamber 19 and from the latter into a spiral passage 20, which surrounds the separating-chamber 17 and communicates with it by means of the opening 21. The water before entering the separating-chamber flows 50 through the spiral passage 20 and is given thereby a rotatory motion and then directed against a cone 22, having its point or apex downward in the center of the separating-chamber, the scum falling from the cone 22 55 into a scum or sludge chamber 23, arranged below the said cone, while the cleaned water rises through the chamber 17 to the filter. An upright cone 26 is likewise arranged in the filtering-chamber 14 for the purpose of facilitating 60 the cleansing of the filtering material in the said filtering-chamber, as herein-after described. From the separating-chamber the water flows upward through the gauze 16 into the filtering-chamber and tends to 65 press the filtering material into the upper contracted part of said filtering-chamber. It then passes through the filtering material and

out of the top end of the filter through the gauze 15 and bend 11, whence it returns in a purified condition through the return-pipe 12 70 into the boiler. The pressure above and below the filtering-chamber being otherwise similar, it is necessary, in order to insure the flow of the water from below upward through the filter, that the cross-sectional area at the 75 bottom should be greater than that at the top in order to correspondingly increase the pressure. The purified water before returning to the boiler is mixed with feed-water or is surrounded by the latter, and thus cooled to a 80 certain degree, which consequently increases the circulatory force due to the denser and therefore heavier descending column of water. At the same time the temperature of the feed-water is increased for the same reason 85 on its entrance into or contact with the return-pipe, and the calcium salts previously held in solution tend to separate from it and sink to the bottom of the boiler, where they are afterward collected in the deposit-collecting 90 tube 6.

Owing to the continual circulation and constant separation of impurities, a clearing out of the filter as well as of the scum-chamber from time to time is unavoidable. To enable 95 this to be done, the scum-chamber 23 is provided with an outlet 24, at the end of which is a valve 25. By opening this valve a fall of pressure takes place in the purifier and its pipes, with the result that the water of the 100 boiler rises high in the return-pipe 12 and flows through the filter from the top downward. The filter-block in the contracted part of the filtering-chamber is thus pressed downward by the water and forced upon the cone 105 26, arranged in the center for the purpose. The water also washes the filtering material—sand, infusorial earth, or the like—removing the impurities therefrom into the scum-chamber 23, from which, together with the impurities it contains, they pass away through the 110 outlet 24. The operation of thus cleansing the filter and clearing out the scum-chamber is performed in a moment. By closing the valve 25 the circulation of the water is 115 restored to its proper condition suitable for purifying the boiler-water. A cock 27 is fitted on the filter in case it should sometimes be necessary to allow air to escape.

Having thus described my invention, what 120 I claim is—

1. In an apparatus of the class described, a steam-boiler, a separating and filtering device, a plurality of raising-tubes connected with said separating and filtering device, and 125 the lower ends of which are located in superposed planes, a deposit-collecting member connected with one of said pipes at the lower end thereof, a second deposit-collecting member located above the other one and connected 130 with said other raising-pipe, and means for conveying water from said separating and filtering device.

2. In an apparatus of the class described,

a steam-boiler, a separating and filtering device, raising-pipes connected with said separating and filtering device, and one of them having a deposit-collecting tube, and the others having oppositely-facing funnels, and the funnels being located above said tube, and means for conducting water from said separating and filtering device.

3. In an apparatus of the class described, a steam-boiler, a separating and filtering device, raising and return pipes connected with said device, and adapted to be also connected with said steam-boiler, and a spiral pipe surrounding the return-pipe.

15 4. In an apparatus of the class described, a separating and filtering device, having a scum-chamber, an inverted cone arranged above said scum-chamber, a separating-chamber in connection with the scum-chamber and 20 inclosing said cone, an annular chamber having an inlet, a spiral passage connecting the annular chamber with the separating-cham-

ber, and a tapered chamber having reticulated top and bottom, and located above and in connection with said separating-chamber. 25

5. In an apparatus of the class described, a separating and filtering device, having a scum-chamber, an inverted cone arranged above said scum-chamber, a separating-chamber in connection with the scum-chamber and 30 inclosing said cone, an annular chamber having an inlet, a spiral passage connecting the annular chamber with the separating-chamber, a tapered chamber having reticulated top and bottom, and located above and in connection with said separating-chamber, a cone 35 in said tapered chamber, and a valved outlet for the scum-chamber.

In witness whereof I have hereunto set my hand in presence of two witnesses.

JOSEPH BÉHA.
